UNITED STATES PATENT OFFICE.

FRANK C. COURSON, OF ALTOONA, PENNSYLVANIA.

BOLT-PULLING DEVICE.

Application filed September 23, 1922. Serial No. 590,196.

To all whom it may concern:

Be it known that FRANK C. COURSON, a citizen of the United States, residing at Altoona, in the county of Blair and State of Pennsylvania, has invented certain new and useful Improvements in Bolt-Pulling Devices, of which the following is a specification.

This invention relates to bolt pulling devices and has for its primary object an improved means of gripping the bolt to be pulled as well as a novel means for pulling the bolt.

Another object of this invention is to provide an improved type of locomotive frame bolt puller which consists primarily of a frame block that is adapted to rest against the frame in which is positioned the bolt to be pulled, while gripping blocks within the frame block are forced against the bolt head by virtue of a wedge action set up through the action of a plurality of screws that pass through the frame block, each bolt passing through the block engages a compression block which is recessed within the frame block.

A further object of this device is to provide a rugged and durable device with few parts which can be manufactured and maintained at a minimum cost.

A still further object of this device is to reduce the high cost of locomotive repairs in locomotive shops as quite frequently it is a difficult and expensive process to remove some of the ream taper fitted bolts in modern locomotive frame construction.

With these and many other objects in view which will be more readily apparent as the nature of the invention is better understood, the same consists in the novel construction, combination and arrangement of parts as will be hereinafter fully pointed out, and claimed.

It will be quite readily understood by those skilled in the art to which this invention belongs that the same is quite susceptible to various changes and modifications without departing from the spirit or scope of the invention, but a preferred and thoroughly practical embodiment of the inven-

tion is shown in the accompanying drawings in which—

Figure 1 is a cross sectional view of my improved bolt puller showing all the various parts in operative relation. 55

Figure 2 is a side elevational view of the frame block shown in Figure 1.

Figure 3 is a plan view of the frame block having all the various operating elements removed therefrom. 60

Figure 4 is an end elevational view of the block shown in Figure 3 of the drawings.

Figure 5 is a front elevational view of one of the bolt head gripping units which are shown in the assembled position in Figure 1 of the drawings. 65

Figure 6 is a side elevational view of the part shown in Figure 5 of the drawings.

Figure 7 is a bottom edge view of the parts shown in Figure 5 of the drawings. 70

Figure 8 shows an elevational view of the filling liner which is shown in cross section in Figure 1 of the drawings.

Figure 9 is an edge view of the filling liner shown in Figure 8. 75

Figure 10 is a plan view of a collar that is adapted to be attached to the end of one of the bolts which are used to back the frame block away from the frame when the bolt puller is used to pull frame bolts out of locomotive frames. 80

Figure 11 is an elevational view of the parts shown in Figure 10 of the drawings.

Similar reference numerals refer to similar parts throughout the several figures of the drawings. 85

In carrying out this invention I provide a frame block designated in its entirety by the numeral 10, which consists primarily of a rectangular metallic piece having a rectangular hole cut therein. The ends of the rectangular hole are made to slope out from the base of the block such that the top of the rectangular opening is longer than the bottom opening. 90

Coacting with the inclined surfaces, 11, is a liner 12, the thickness of which is varied according to the diameter of the bolt head of the bolt to be extracted. The liner 12 is provided with a ledge 13, the face 14 of 100

which is adapted to engage the surface 15 of the frame block 10 as shown in Figure 1 of the drawings.

The liner 12 is preferably finished on both 5 sides 16 and 17 in order to provide a smooth unobstructed surface for the parts that coact in conjunction therewith. The surface 17 is engaged by an inclined surface 18 of a bolt head gripping block designated by the 10 numeral 19, shown in detail in Figures 5, 6 and 7 of the drawings.

The bolt head gripping block 19 is provided with a plurality of gripping faces 20 each of which grips a side of the bolt head. 15 The gripping faces are each preferably provided with a thread or toothed like surface 21 which serves in a very practical way to prevent any slippage after the pulling effort has been applied.

20 The block 10 is further provided with a plurality of threaded openings 22 and 23, in each of which is adapted to fit a threaded bolt 24, the end 25 of which is adapted to rest in an annular collar 26, which is suitably secured to the end of the bolt 24 to 25 facilitate handling.

In assembling this improved bolt puller around a bolt to be extracted the block 10 is placed over the bolt head 27 and the gripping blocks 19 are placed on each side of the 30 head as shown in Figure 1 of the drawings; liners 12 are then inserted between the taper faces of the jaw and the tapered face of the block 10. The thickness of the liner 35 12 is governed by the size of the bolt head. The faces 29 of the gripping block 19 are separated such that when the full gripping action is exerted the faces do not impinge against one another.

40 The screws 24 are then adjusted such that the surface 30 rests against the surface from which the bolt is to be extracted. The bolts 24 are each turned down thus forcing the frame block 10 away from the frame on 45 which the block is adapted to rest when the bolt puller is applied to the bolt. The first action when pulling a bolt is to force the sur-

face 21 of the block 19 into the surface of the bolt head. Further removal of the block 10 from the frame serves to extract the bolt 50 which is easily accomplished without effort or danger.

Having thus described my invention what I claim and desire to be secured by 55 Letters Patent is—

1. A bolt pulling device comprising a head having a central inclosed opening provided with downwardly and inwardly inclining end walls, and also having threaded openings terminating in enlarged socket portions open at the bottom face of the body, said openings being located between the said inclined walls of the central opening and the ends of the body, screws adapted to be inserted in said threaded openings having 60 swivelled bearing feet arranged in said sockets, and bolt-head clamping portions detachably fitted in said central opening and cooperating with the inclined walls to grip the bolt-head upon the upward movement 65 of the body.

2. A bolt pulling device comprising in combination a body having a central opening provided with downwardly and inwardly inclined end walls, screws having a 70 threaded engagement with the body and projecting through one face thereof to engage an abutment surface, removable bolt-head gripping portions adapted to be arranged in said central opening, and liner plates 75 adapted to be interposed between said gripping portions and the inclined walls of the opening.

3. A bolt pulling device comprising in combination a body provided with a central opening having opposite converging walls, lifting screws carried by the body, and a plurality of detachable bolt-head gripping portions and detachable liners cooperating therewith to adapt the device to engage bolt-heads of different sizes.

In testimony whereof he affixes his signature.

FRANK C. COURSON.
